BALL POINT PEN

Herbert W. Sams and Charles K. Lovejoy, Atlanta, Ga.,
assignors to Scripto, Inc., a corporation of Georgia

Application April 24, 1959, Serial No. 55,651

Term of patent 14 years

(Cl. D74—17)

Fig. 1 is a front elevational view of a ball point pen embodying our new design;

Fig. 2 is a side elevational view thereof;

Fig. 3 is an enlarged top plan view;

Fig. 4 is an enlarged bottom plan view; and

Fig. 5 is an enlarged sectional view taken on the line 5—5 of Fig. 1, the details of the interior construction of the pen having been omitted.

We claim:

The ornamental design for a ball point pen, as shown and described.
